(57) **CLAIM**

The ornamental design for a receiver for a baby monitor, as shown and described.

DESCRIPTION

FIG. 1 is a top front perspective view of a receiver for a baby monitor according to my new design, with a stand of the receiver in a retracted position.

FIG. 2 is a top rear perspective view thereof, with the stand in the retracted position.

FIG. 3 is a right side view thereof, with the stand in the retracted position.

FIG. 4 is a front view thereof, with the stand in the retracted position.

FIG. 5 is a left side view thereof, with the stand in the retracted position.

FIG. 6 is a rear view thereof, with the stand in the retracted position.

FIG. 7 is a top view thereof, with the stand in the retracted position.

FIG. 8 is a bottom view thereof, with the stand in the retracted position.

FIG. 9 is a top front perspective view of the receiver of FIG. 1, showing the stand in an intermediate extended position.

FIG. 10 is a rear perspective view of the receiver of FIG. 1, showing the stand in the same intermediate extended position shown in FIG. 9.

FIG. 11 is a left side view of the receiver of FIG. 1, showing the stand in another intermediate extended position.

FIG. 12 is a left side view of the receiver of FIG. 1, showing the stand in the same intermediate extended position shown in FIG. 9; and,

FIG. 13 is a left side view of the receiver of FIG. 1, showing the stand in a fully extended position.

The broken line showing of parts of the drawings is included for the purpose of illustrating use and environment and forms no part of the claimed design.
